UNITED STATES PATENT OFFICE.

ERNEST B. KITCHEN, OF WHITE POST, VIRGINIA.

MAIL-BOX SIGNAL.

No. 823,791.

Specification of Letters Patent.

Patented June 19, 1906.

Application filed February 12, 1906. Serial No. 300,772.

To all whom it may concern:

Be it known that I, ERNEST B. KITCHEN, a citizen of the United States, residing at White Post, in the county of Clarke and State 5 of Virginia, have invented certain new and useful Improvements in Mail-Box Signals, of which the following is a specification.

My invention relates to certain new and useful improvements in mail-boxes and signals therefor, and particularly to that type 10 of mail-box intended for individual use along rural-free-delivery routes. Mail-boxes of this character are usually placed along the main road, and hence they are very often at a 15 considerable distance from the residence of the party or parties using the box, and it has been found essential or advantageous to provide these boxes under the circumstances with visible signals that will indicate to the 20 carrier that mail has been deposited in the box for his collection, so that he will not have to alight unnecessarily, and to indicate to the householder that mail has been deposited in the box by the letter-carrier, thereby avoiding 25 the necessity of his making a useless trip to the box to ascertain whether or not the latter contains mail-matter.

It is the object of my invention to provide improvements in these signaling devices, 30 such improvements being characterized by exceeding simplicity and cheapness of manufacture, durability, and efficiency of operation.

To this end the invention consists of a 35 rural-free-delivery mail-box provided with a visible signaling device consisting of few and simple parts and embodying a target which is designed to be manually moved to the display position whenever desired and automatically retained in such position and which 40 will be automatically released and dropped by its own weight to the inoperative or concealed position when the lid of the box is raised to extract the deposited mail-matter 45 therefrom.

For a full description of the invention and the merits thereof and also to acquire a knowledge of the details of construction of the means for effecting the result reference is 50 to be had to the following description and accompanying drawings, in which—

Figure 1 is a perspective view of my improved mail-box. Fig. 2 is a transverse sectional view thereof and illustrates the lid 55 closed and the target or signal in the display

position. Fig. 3 is a similar view and illustrates the lid partially open and the signal dropped to the inoperative position. Fig. 4 is a detail perspective view of the three simple parts of which my invention is comprised.

Corresponding and like parts are referred to in the following description and indicated in all the views of the drawings by the same reference characters.

Referring to the drawings, the numeral 1 indicates the body of the box, which is preferably composed, as well as the hinged lid 2, of sheet metal, so that it will be durable and substantially proof against the action of the 65 elements. The lid 2 is hinged to the top of the box and at the upper rear edge thereof, as indicated in Figs. 2 and 3. To the under side of the lid there is secured a leaf-spring 3. The spring 3 is screwed or riveted at its rear 70 end to the lid 2 and is provided with a free or unattached angular portion 4, offset somewhat from the under surface of the lid and extending substantially at right angles to the axis about which the lid turns. The spring 3 75 is preferably formed at the extremity of its free or offset portion 4 with a downwardly-extending portion returned upon itself to form a V-shaped lug 5. This construction produces a lug of sufficient strength in a 80 simple and cheap manner.

The signal proper is constituted by an arm 6, pivoted at its end to one side of the box and designed to swing about such end in a 85 vertical plane. The arm 6 carries at its free 90 end a target 7, which is preferably integral therewith and which may be of any desired form or design. Preferably it is of some contrasting color, so as to be readily discernible. In the preferable construction of the arm 6 95 it is provided with an integral pivoted stud 8, mounted in a bearing-aperture in the side of the box and extends through said side to the inner face thereof, where it is provided with a reduced extension 9. A detent 10 is securely 100 fastened on the extension 9 of the pivoted stud 8, so as to turn therewith and with the arm 6, and the detent is so positioned with respect to the arm and to the lug 5 at the free 105 end of the spring 3 that when the lid 2 is down, or in its lowered position, the lug will stand in the path of the detent, so that the arm carrying the target 7 may be manually turned to the raised or display position and the detent pushed past the lug 5 and be held 110

thereby, so as to maintain the target in the raised position. The detent 10 is preferably formed at one side with a cam-surface 11, which assists in its action in passing the lug 5. The lid may be secured in its lowered position by means of a padlock 12 or similar device.

From the foregoing description, in connection with the accompanying drawings, it will be seen that when the lid 2 of the mail-box is in its lowered position and mail has been deposited therein, as by means of the slot 13, visible indication of this fact may be effected by manually raising the arm 6 so as to bring its target to the display position, in which it will be held by the detent 10 being engaged by the lug 5. As soon, however, as the lid 2 is raised to extract the mail-matter from the box the arm 6, with its target 7, will drop to the inoperative and out-of-the-way position, (illustrated in Fig. 3,) owing to the fact that the spring 3 is carried by the hinged lid 2, and that therefore the lug 5 of the spring will be carried out of engagement with the detent 10 when the free end of the lid 2 is raised. It will be seen that I have provided a device of the character herein set forth which embodies very few and simple parts, so that it may be cheaply manufactured, and is not liable to get out of order, while at the same time it will be efficient in operation. Preferably in order to prevent the arm 6 from being turned back past the center a stop lug or stud 14 projects from the side of the box, and the position of said lug is such, as well as the relative position of the other parts, that the arm 6 in raised position will be held at one side of its center, so that when the detent 10 is released it will fall by its own weight.

Having thus described the invention, what 40 is claimed as new is—

1. A device of the character described comprising a box provided with a lid, a spring secured at one end to the under side of said lid and provided at its free end with a 45 downwardly-extending lug, a signal-arm provided with a target and hinged to the side of said box, and a cam-detent connected with said arm to move therewith, the arm being arranged for manual actuation and the detent being designed to spring past the lug with the lid in the lower or closed position, so that the lug will engage with the detent and hold the arm with its target in the visible position.

2. A device of the character described, comprising a mail-box provided at its top with a hinged lid, a spring secured at one end to the under side of said lid and provided with a portion offset from the under side of 60 the lid and formed at its extremity with a downwardly-extending portion returned upon itself to form a lug, an arm provided at one end with a pivoted stud mounted in one side of the box, said stud extending through 65 the box, a cam-detent secured to the extension of said stud and designed to spring past said lug with the lid in the lowered position whereby said lug will engage the detent and hold the arm raised, and said arm carrying at 70 its other end a target, as and for the purpose set forth.

In testimony whereof I affix my signature in presence of two witnesses.
